UNITED STATES PATENT OFFICE.

WILLIAM GENTRY SHELTON, OF NEW YORK, N. Y.

DENTAL-ENGINE HAND-TOOL.

1,201,362.

Specification of Letters Patent. Patented Oct. 17, 1916.

Application filed April 18, 1911. Serial No. 621,746.

To all whom it may concern:

Be it known that I, WILLIAM GENTRY SHELTON, a citizen of the United States, residing in the borough of Manhattan, city, 5 county, and State of New York, have invented certain new and useful Improvements in Dental-Engine Hand-Tools, of which the following is a specification.

This invention relates to dental engines, 10 and aims to provide certain improvements therein.

One of the objects of this invention is to provide a self-contained dental engine hand-tool, the arrangement and location of the 15 parts being so organized that the tool balances itself properly in the hand, and is of such light and efficient construction that it performs its work with the highest degree of satisfaction, one feature making for this 20 satisfactory result being the location of the transmission gear rearwardly of the electric motor, the drill stock being carried at the front of such motor.

It is the object of the present invention 25 to provide a dental engine adapted to be electrically operated, in which the motor is preferably located upon and carried by the dental hand-piece, and in which the controlling member of the drill or other tool is 30 preferably arranged close to the hand of the operator.

In the preferred form of the invention the device is of extremely cheap and simple construction, light in weight, and easily 35 moved from one position to another so that it may be conveniently operated in any position on either side of the patient.

The invention includes certain other improvements which will be hereinafter more 40 fully pointed out.

Referring to the drawings, which illustrate one form of the invention, Figure 1 is a central vertical section; and Fig. 2 is a top or plan view.

45 A self-contained dental-engine hand-tool is shown in the illustration and is designated as a whole by the reference character A, and comprising a motor or engine portion B carried at the rear of the dental hand-piece or chuck member C. The motor or engine B comprises in the illustration an electric motor, the armature D of which is preferably mounted to rotate in line with the hand-piece C, within a stationary field 50 E. The armature is shown provided with a hollow armature shaft I, extending for-

wardly and rearwardly of the motor. The armature and field are preferably arranged within a suitably shaped casing F having at its lower end a hollow projection or bearing G. Within the bearing G is arranged a fixed shaft H which extends upwardly within the armature so as to provide a stationary bearing for the latter.

As the armature in this type of motor rotates at very high speed, which is not suitable for dental work, I provide a means for reducing the speed of the drill shaft to that which may be safely employed in dental operations. To this end the armature has 65 fixed to it the shaft I the rearwardly extending end of which is provided with a gear J which meshes with a pinion K fixedly mounted upon a countershaft L, the latter also carrying a small pinion M fixed to the 70 pinion K and which in turn meshes with a gear N fixed upon a shaft O which passes through the hollow shaft I. In order to maintain the shaft O in position, it is formed with a groove P adapted to receive a set 75 screw Q which permits the shaft to rotate while holding it against longitudinal displacement.

The hand-piece C is of some suitable form, and is provided at its lower end with a 80 chuck or other means for engaging a drill 85 stem, disk holder or the like. As such hand-pieces are well known, it will not be here described in detail. It is sufficient to say that the hand piece is provided with a shaft R passing out of its rear end, to which is fixed one part S of a coupling member, the other part T of which is carried by the shaft O. Such coupling 90 member preferably includes a projection 95 S' which is adapted to fit into a recess in the member T, the coupling member S being also provided with a socket S² adapted to receive a centrally arranged spring nipple T'. This form of coupling, which is well 100 known, provides for a ready connection of the parts. The counter shaft L and shaft R together constitute a tool spindle mounted in the hand-piece and extending through the hollow armature shaft rearwardly of 105 the motor. The transmission gearing between the said armature shaft and tool spindle is shown located rearwardly of the said motor,—that is assuming the hand-piece to be at the front of the hand-tool.

110 The motor casing is preferably supported by the shell of the hand-piece C, and to this

end a sleeve U is preferably provided which is adapted to screw on the lower part of the motor casing and the upper part of the hand-piece as shown, such sleeve covering 5 the connection or joint between the shafts of the two parts. It is often desirable that the hand-piece C shall be capable of rotation relatively to or independently of the motor casing. This is particularly true in the use 10 of angled hand-pieces. I therefore prefer to form the sleeve U in two parts, and to swivel these parts together as by the bead connection shown, or in any other suitable way.

My invention also provides means for controlling the operation of the drill or other tool, and this is preferably accomplished by a control of the motor, although other methods may be adopted for that purpose. In the construction shown I provide an operating handle V, which is preferably located conveniently to the thumb of the operator, so that by an upward or downward movement the motor may be started, stopped or reversed. A movement of the arm V from 25 either of its extreme positions toward the center, will stop the motor, while a movement from its middle position to either end will start or reverse the motor, according to the arrangement of the parts. Many other 30 constructions may be adopted for controlling the motor. It is desirable, however, that the controlling member shall be so located as to be within convenient reach of the operator, and preferably within reach of the hand of 35 the operator which is holding the device.

It will be readily apparent that the transmission mechanism is of relatively light weight, and that the core structure of the motor is arranged closely adjacent the hand- 40 piece, whereby the center of gravity of the mechanisms carried by the hand-piece, and shown in the illustration disposed within the casing, is brought toward the hand of the operator when the instrument is in use.

45 In the construction thus described a very light and cheap form of motor may be used, and the entire device is of simple and

economical construction. Moreover the device is capable of use in any position, being restricted only by the length of the electric 50 cable X which is utilized to lead the current to the motor.

While I have shown in detail one form of the invention, it will be understood that I do not wish to be limited thereto, as many 55 changes may be made therein without departing from the spirit of the invention.

The feature herein illustrated of having the finger-piece extending along and entirely disconnected from the hand-piece, is 60 claimed in my co-pending application, Serial No. 765,263, filed May 3, 1913.

What I claim is:—

1. A dental-engine hand-tool comprising a dental hand-piece, an electric motor carried 65 at the rear of the hand-piece and having its core structure arranged closely adjacent thereto and having a rearwardly extending armature shaft, a tool spindle mounted in the hand-piece and extending rearwardly of 70 said motor, and transmission gearing between the said shaft and spindle and located rearwardly of the said motor, said transmission mechanism being of relatively light weight. 75

2. A dental-engine hand-tool comprising a dental hand-piece, an electric motor carried at the rear of the hand-piece and having its core structure arranged closely adjacent thereto, and having an armature shaft, a tool 80 spindle mounted in the hand-piece, said shaft and spindle being mounted one within the other and extending rearwardly of said motor, and transmission gearing between the said shaft and spindle and located rear- 85 wardly of the said motor, said transmission mechanism being of relatively light weight.

In witness whereof, I have hereunto signed my name in the presence of two subscribing witnesses.

WILLIAM GENTRY SHELTON.
